TELEPHONE STERILIZING ATTACHMENT

Allen Grobman, Chicago, Ill.

Application July 24, 1956, Serial No. 42,360

Term of patent 3½ years

(Cl. D26—14)

The single figure is a perspective view of a telephone sterilizing attachment, showing my new design.

The broken line showing of a telephone is for illustrative purposes only.

I claim:

The ornamental design for a telephone sterilizing attachment, as shown and described.
